(57) **CLAIM**

The ornamental design for a bicycle frame with training wheel brackets, as shown and described.

DESCRIPTION

FIG. 1 is a perspective view of a bicycle frame with training wheel brackets showing my new design;

FIG. 2 is another perspective view thereof;

FIG. 3 is a side elevational view thereof, the opposite side being a mirror image;

FIG. 4 is a top plan view thereof;

FIG. 5 is a front elevational view thereof;

FIG. 6 is a rear elevational view thereof; and,

FIG. 7 is a further perspective view thereof.

The broken lines showing of FIGS. 2-7 are for illustration purpose only and therefore establish no part of the claimed design.
